[57] ABSTRACT

A metal band producing plant in which there is provided rotating rolls for crystallizing molten metal into a band, with said rolls having a crystallizing zone which is limited by annular projections whose height is less than half the thickness of the crystallizing band and which zone is located at such a distance from the roll ends as to ensure a minimum relative deformation of the rolls in the crystallizing zone.

PLANT FOR PRODUCING A METAL BAND FROM A MELT

BACKGROUND OF THE INVENTION

The present invention relates to foundry equipment and more specifically to metal band producing plants.

The present invention is used most effectively for producing metal band up to 3-4 mm thick from iron-nickel-and copper-base alloys. The produced band can be cut for use in the form of separate sheets.

Besides, the invention can be utilized for producing metal band up to 10 mm thick from alloys based on aluminium and iron.

PRIOR ART

Widely known in the art is the metal band producing plant utilizing the method of continuous casting on rotating rolls for crystallizing molten metal into a band, with surplus metal being freely discharged at the roll ends.

In the known plant, the molten metal is poured into the interroll space formed by the closed rotating rolls cooled with water from the inside. The butt ends of the rolls are provided with built-in flanges. Rising to a certain level in the interroll space, the molten metal forms a wedge. Coming in contact with the roll surface, the molten metal in the wedge cools down and crystallizes. The crusts of solid metal formed on the surface of the rolls are welded to each other and leave the rolls in the form of a band.

The disadvantages of the known plants are as follows. Crystallization of metal proceeds on the working zone of the rolls which is equal, or nearly equal, to the total length of the rolls.

Accordingly, formation of the edge portions of the band is seriously influenced by the solid flanges built into the roll ends. Said flanges impair the cooling of the rolls at the end and interfere with their expansion in this zone when they are heated by the crystallizing metal. As a result, the rolls bulge out in the middle to a larger extent than at the ends.

Experiments have shown that rolls 500 mm in diameter and 500 mm long with walls 10-15 mm thick bulge out in the middle up to 1.5 mm. At the same time, no bulging has been registered near the flanges.

Irregular deformation of the roll increases the clearance between the working surfaces of the rolls at the end zones which reduces the contact between said rolls and the crystallizing metal. This impairs the stability of band formation and increases variations in the band thickness which affects adversely the quality of the produced band.

OBJECTS AND SUMMARY OF THE INVENTION

An object of the invention resides in eliminating the aforesaid disadvantages.

The main object of the invention is to provide a metal band producing plant which ensures stable forming and a uniform thickness of the band.

This object is accomplished by providing a metal band producing plant utilizing the method of continuous casting on rotating rolls for crystallization of molten metal into a band with surplus metal freely discharged at the roll ends wherein, according to the invention, the rolls have a crystallizing zone which is limited by annular projections whose height is less than half the thickness of the crystallizing band and which

zone is located at such a distance from the roll ends as to ensure a minimum relative deformation of the rolls in the crystallizing zone.

It is practicable that the crystallizing zone be located 5 150-250 mm from the roll ends.

Now the invention will be described in detail by way of example with reference to the accompanying drawings in which:

BRIEF DESCRIPTION OF THE DRAWINGS

FIG. 1 is a general view in longitudinal section and partly cut away of the plant according to the invention;

FIG. 2 is a view along arrow A in FIG. 1; and

10 FIG. 3 is an enlarged view showing relative positions 15 of the rotating rolls and metal band according to the invention.

DETAILED DESCRIPTION OF THE INVENTION

The metal band producing plant utilizing the method 20 of continuous casting, according to the invention, comprises a frame 1 (FIG. 1) accommodating rolls 3 mounted in bearings 2 for crystallizing molten metal into a band, with said rolls being pressed against each other and rotating in opposite directions as shown in 25 FIG. 1.

According to the invention, the rotating rolls 3 have a zone 5 (FIG. 2) on their outer surfaces 4, with said zone being provided for the crystallization of molten metal and forming of a band 6 (FIG. 3). The crystallizing zone 5 is limited by annular projections 7 (FIG. 2) located on the outer surface 4 of the rolls 3 and is set at such a distance from butt ends 8 of the rolls 3 as to ensure a minimum relative deformation of the rolls in the zone of their contact with the molten metal, i.e., in 30 the crystallizing zone 5.

The most rational distance between the crystallizing zone 5 and the butt ends 8 of the rolls 3 which ensures a minimum relative deformation of rolls 3 in said zone is 150-250 mm.

40 In addition, this distance ensures stable deformation of the crystallizing band 6 which in turn, ensures minimum variations of the band thickness. The height of the annular projections 7 is set to be less than half the thickness of the crystallizing band 6. On these projections 7 are crystallized edges 9 of the band 6, with said edges being thinner than the main part of the band 6.

45 Due to the fact that the edges 9 of the band 6 are thinner and, correspondingly, have a lower temperature of crystallization, their strength within this temperature range is higher than that of the main band which rules out the destruction of the band edges as the band leaves the rolls.

The rolls 3 are pressed together by a hydraulic piston cylinder 10 (FIG. 1) through housings 11 of the bearings 2 which can slide over the guides located on the frame 1.

50 The rolls 3 are rotated by a drive 13 via a cardan shaft 14 (FIG. 2) connected with journals 15 secured on the butt ends 8 of the rolls 3.

60 The surplus metal 16 (FIG. 3) is freely discharged through means 23 located in the butt ends of the rolls 3; then, it is accumulated and removed by conduits 17 (FIG. 1) installed under the butt ends 8 of the rolls 3 on trolleys 18 which have a travelling motion drive (not shown in the drawings).

65 Any droplets of metal stuck to the outer surfaces 4 of the rolls 3 can be cleaned off by wire brushes 19

mounted on the frame 1 and provided with an individual rotation drive 20 (FIG. 2).

In order to remove the heat at the process of crystallization of metal into the band 6, the rolls 3 are cooled with water flowing into and out of the rolls 3 through holes 21 (FIG. 1) which are located in the journals 15 of the rolls 3.

The metal band producing plant covered by the present invention operates as follows:

The drive 13 for rotation of the crystallizing rolls 3 is turned on after which the rolls 3 are pressed together by the hydraulic piston-cylinder unit 10. The molten metal is poured from a ladle or furnace (not shown in the drawings) into the receiving-and-distributing device (not shown in the drawings) from which it is fed onto the rolls 3, forming a wedge-shaped bath of liquid metal in the gap between the outer surfaces 4 of the rolls 3.

Coming in contact with the rolls 3, the molten metal cools down and starts crystallizing in the layers immediately adjoining the roll surfaces 4. The rotating rolls carry the crystallizing layers of metal into the roll closing zone where these layers acted upon by the pressing force are welded into a continuous band 6 which leaves the rolls 3 and enters a band stripper 22.

The amount of molten metal fed onto the rolls 3 is somewhat larger than required in order to carry away any scabs, nonmetallic inclusions, etc. accumulating on the surface of the metal bath. The surplus metal 1 is discharged at the butt ends of the rolls through drainage grooves and accumulated in the conduits 17.

When the band 6 is formed on the surfaces 4 of the

rolls 3, the molten metal crystallizes in that zone of the rolls whose deformation is relatively uniform throughout its length. This provides for a constant contact between the crystallizing metal and the roll surfaces and stabilizes the process of band formation.

The formed band 6 with narrow thin strips at the edges 9 formed on the projections 7 moves undamaged into the band stripper 22 and thence it is carried for winding into a coil. The band thus formed can be used later for making metal sheets.

Formation of metal band in the plant according to the invention ensures stable production of cast metal bands and, if necessary, sheets with a satisfactory surface and uniform thickness.

What is claimed is:

1. A plant for producing a metal band utilizing the continuous casting method and comprising: internally cooled rotatable rolls for crystallizing molten metal into a band; means for feeding molten metal between the rolls; a drive for rotating said rolls; said rolls being provided with axially spaced annular projections, the height of the projections being less than half the thickness of the crystallizing band and which projections limit the crystallizing zone, said zone being located at such a distance from the roll ends as to ensure a minimum relative deformation of said rolls in the crystallizing zone; and the surplus metal being freely discharged at the ends of the rolls.

2. The plant as of claim 1 wherein the crystallizing zone is located 100-250 mm from the roll ends.
